UNITED STATES PATENT OFFICE.

FRANZ SCHMIRK, OF GROSSENHAIN, SAXONY, GERMANY.

POSITIVE SHUTTLE-MOTION FOR LOOMS.

SPECIFICATION forming part of Letters Patent No. 402,354, dated April 30, 1889.

Application filed May 12, 1888. Serial No. 273,710. (No model.) Patented in Germany November 12, 1886, No. 40,573, and May 1, 1887, No. 42,749; in England June 24, 1887, No. 9,014, and in Austria-Hungary November 16, 1887, No. 21,050 and No. 52,779.

To all whom it may concern:

Be it known that I, FRANZ SCHMIRK, a subject of the King of Saxony, residing at Grossenhain, Kingdom of Saxony, Germany, 5 have invented new and useful Improvements in Positive Shuttle-Motions, (for which Letters Patent have been granted in Germany, No. 40,573, November 12, 1886, and No. 42,749, May 1, 1887; Great Britain, No. 9,014, June 10 24, 1887, and Austria-Hungary, Nos. 21,050 and 52,779, November 16, 1887,) whereof the following is a specification.

My invention relates to positive shuttle-motions for looms; and the improvements 15 consist in the particular construction of the mechanism for actuating the shuttle and of the shuttle itself.

On the annexed drawings the said mechanism is represented by Figure 1 in elevation, 20 looking upon the back of the batten. Fig. 2 is a sectional view on lines 1 1 and 2 2 of Fig. 1; Fig. 3, a sectional plan on line 3 3, Fig. 1; and Fig. 3^a, a vertical section through cam-disk F. Fig. 4 is an elevation, and Fig. 5 a 25 plan, of one of the grippers by which the shuttle is held and moved. Fig. 6 is an end view of a gripper and portion of mechanism for opening and closing the same, and Fig. 7 a plan of the shuttle. Figs. 8 and 9 are 30 respectively transverse and longitudinal sections of the shuttle, the latter being taken on line 4 4, Fig. 7, and the former at right angles to said line.

In Figs. 1 and 2, A is the batten, to the 35 respective ends of which are fixed the guides a a, on which slide with their base-plates b b' the grippers B B, the said plates b b' having dovetail ledges engaging in like grooves of the guides. As shown by Fig. 4, each gripper 40 consists of the base-plate b b' as lower jaw, and of the lever b, forming the upper jaw, the latter being acted upon by a spring, h, which tends to keep the gripper open. At its operating end the said upper jaw is provided 45 with teeth i, adapted to engage with like teeth formed upon the shuttle C, Figs. 7, 8, and 9, which carries the weft-spool O.

For operating the shuttle the two grippers require to be simultaneously moved from their

outer position toward the center of the batten and back again, and, besides, at the moment the grippers are at the end of their inward stroke the one has to close so as to seize the shuttle which has been carried toward it by the opposite gripper, and the latter has to open in order to release the same, the shuttle being thus alternately delivered from one gripper to the other. These motions are brought about by the following mechanisms:

The to-and-fro motion of each gripper is produced by a cam-cylinder, N, and the two levers H and u, the lever H being provided with a finger, c, that projects into the cam-groove of the cylinder N, and the lever u, 60 which is pivoted at u', engaging by means of an elongated eye with the end of the lever H, while at its upper end it is connected by a short link, u'', to the base-plate of the gripper. The two cylinders N are keyed on the 65 ends of a shaft, y.

For causing the grippers to open and close alternately at the proper moment and to remain, respectively, open and closed in the interval, the tail ends of the upper jaws, b, provided each with a projection or pin, f, preferably fitted with a roller, are acted upon by oscillatory bars d, pivoted at m and n to the batten, and the upper edge and axis of oscillation thereof are parallel to the lines of 80 motion of the grippers. These bars have each an arm, d', (see Figs. 2 and 6,) and they are connected, by means of the said arms and of rods v, to the ends of a lever, x, having its fulcrum at x'. The consequence of this arrangement is that when the left-hand bar d is raised, and is thus caused to act from below against the roller on the pin f above it, it will keep the corresponding gripper closed during 85 its entire stroke as the said roller rolls along the bar. The right-hand bar d is meanwhile kept depressed on account of the connection of the bars with each other by the rods v and lever x, so that the right-hand gripper is then maintained open by its spring h.

The lever x is connected at one end by means of a universal joint—such as a ball-and-socket joint—to a lever, w, pivoted at w',

and engaging with a finger, w^2 , Fig. 3^a, in a grooved cam-disk, F, adapted to cause the bars d to be quickly raised and depressed through the medium of the connecting parts. The disk is keyed on a shaft, q, which is connected to the shaft y by the spur-wheels E and D, whereof E is twice as large as D, thus giving the shaft q one-half the speed of shaft y, so that each gripper will make full strokes with its jaws alternately open and closed, and the disk is so arranged relatively to the cam-cylinders N that the opening and closing of the grippers will take place when they are at the end of their motion toward each other. To the shaft y motion is transmitted from the crank-shaft of the loom by suitable gearing. (Not shown in the drawings.)

In the shuttle shown by Figs. 7, 8, and 9 the teeth designed to be engaged by those of the grippers are formed upon plates k, lodged in recesses l of the shuttle, and pressed upward against shoulders l' by springs k', the plates k being thus adapted to yield and to cause the shuttle to become disengaged from the gripper that holds it in case an unusual resistance should occur. In order to increase the containing capacity of the spool, as compared with spools of the ordinary kind, and to allow of an easy winding off of the weft thread or wire, especially if the same is thick or stiff, the spool is arranged with its axis vertically in the shuttle. For this purpose the portion of the shuttle containing the gripping-surfaces is provided at the bottom with an arm or carrier, p, to which is fixed a vertical pin, r, serving as a pintle for the spool to rotate on. The spool is prevented from accidentally flying off the pin by means of a plate, s, hinged to the shuttle and acted upon at its rear end, which is square, by a spring, t, in the manner of a clasp-knife. To the plate s is fixed a spring, o, bearing upon the spool and serving to check its rotation if the same should become excessive. The spool is guarded by a bow, h, having a hole for the weft-thread to pass through. This arrangement of spool may also be applied to shuttles of other construction and operated by known means.

I claim as my invention—

1. In a loom, the combination, with the batten A, of the guides a, the grippers B, having each a pivoted jaw, b, provided with teeth i and projection f, mechanism for positively moving the grippers toward and away from each other, the bars d, hinged to the batten and having each an arm, d', and an edge parallel to the guides a, adapted to bear against the projections f, and means connected with said arms d' for oscillating the bars d and pressing their edges against the projections f, substantially as set forth. 50
2. In a loom, the combination, with the batten A, of the guides a, the grippers B, having each a movable toothed jaw, b, with projection f, the shaft y, with cam-cylinders N, means of connection between the cylinders N and the grippers, the oscillating bars d, shaft q, with cam disk or disks F, means of connection between the disk or disks F and the bars d, and gear-wheels connecting together the shafts y and q, substantially as and for the purpose specified. 60
3. In a shuttle, the combination, with the body of the shuttle having recesses l, with shoulders l', of the toothed gripping-plates k, lodged movably in the said recesses, and springs k', pressing the plates k against the shoulders l', substantially as and for the purpose set forth. 70
4. The combination, with the batten A and the shuttle having teeth, of the grippers B, each having a pivoted jaw provided with teeth adapted to engage said shuttle, mechanism for moving said grippers toward and from each other, a cam operating in unison with said mechanism, the pivoted lever x, operated by said cam, and bars connected to the respective ends of said lever x and arranged to engage with and oscillate said pivoted jaws, as set forth. 80

In testimony whereof I have hereunto set my hand in the presence of two subscribing witnesses.
